COMBINED AGITATOR AND PHOTO PRINT CARRIER

Herbert F. Diegel, 1524 E. Culver St.,
Phoenix, Ariz. 85006

Filed Nov. 5, 1971, Ser. No. 196,245

Term of patent 14 years

Int. Cl. D16—04

U.S. Cl. D61—1 P

FIG. 1

FIG. 2

FIG. 1 is a front perspective view of a combined agitator and photo print carrier showing my new design, the rear being a mirror image thereto;

FIG. 2 is an enlarged sectional perspective view of the handle/clasping means therefor;

FIG. 3 is an enlarged perspective view of FIG. 2 in an open position.

I claim:

The ornamental design for a combined agitator and photo print carrier, as shown and described.
